UNITED STATES PATENT OFFICE.

OYSTEIN RAVNER, OF CHRISTIANIA, NORWAY, ASSIGNOR TO DET NORSKE AKTIESELSKAB FOR ELEKTROKEMISK INDUSTRI, OF CHRISTIANIA, NORWAY, A BUSINESS ENTITY, OF CHRISTIANIA, NORWAY.

METHOD OF CONDENSING ZINC VAPORS.

Application filed February 24, 1919. Serial No. 278,977.

To all whom it may concern:

Be it known that I, OYSTEIN RAVNER, a subject of Norway, and a resident of Christiania, Kingdom of Norway, have invented 5 certain new and useful Improvements in the Methods of Condensing Zinc Vapors, of which the following is a specification.

This invention relates to the production of metallic zinc and has for its object a 10 method whereby zinc may be recovered from its ores in a continuous process with great economy and with a comparatively small loss of metal in the form of zinc dust.

In the electrothermic processes hitherto 15 known for the production of zinc the gases have for the most part been led from the distillation chamber through comparatively long, vertical condensation channels to a receptacle for the condensed product. During 20 their passage through these channels the gases have gradually cooled and a separation of carbon monoxide gas and zinc vapors has to some extent taken place.

Such methods of working facilitate the 25 formation of fog and oxidation of the metal due to the influence of CO_2 formed by decomposition of CO according to the equation

30 Contrary to such practice I avoid the disadvantages mentioned by subjecting the gases from the furnace to an intense and sudden cooling, thus causing the gases to pass rapidly that interval of temperature in which the 35 transformation of CO to CO_2 and consequently oxidation of zinc may take place. As a result hereof and also due to the comparatively small size of the condensing surface needed when such intense cooling is 40 used, the formation of zinc dust is reduced to a minimum.

I have found that under certain conditions it may be advantageous not only to apply intense cooling to that part of the 45 condensation channel which is nearest to the distillation chamber but also to cool the rest of the channel whereby the total condensing surface may be further reduced.

Further I have found that intense cooling 50 and reduced condensing surface tend to favor the formation of greater drops of liquid metal than would be obtained by the usual slow cooling, and these drops will during their fall through the gas cause a

precipitation of the fine particles forming 55 a fog. Thus by my method of working, conditions are favorable for a rapid and effective separation of metal vapor from accompanying carbon monoxide gas.

As will be understood from above remarks, my process may be carried out in many different ways. It is especially suitable for the production of zinc but may also be used for other metals of similar qualities. 60 65

The furnace construction may be of any well known type as my present invention only deals with the treatment of the gases and vapors escaping from the furnace. As a rule, however, an electric furnace will be 70

The above described sudden cooling of the gases may be effected by any suitable type of cooler, but I prefer to use water-cooling of the gas channel. In order to render the 75 cooling as effective as possible I have found it advantageous to make the channel of a material having high heat conductivity. I have obtained good results by making the channel of iron or other metals which have 80 no great tendency to alloy with zinc.

I have illustrated my invention in the accompanying drawings forming part of this application. Figures 1, 2 and 3 represent different modifications of my invention. In 85 Figure 1 the numeral 1 designates an electric zinc furnace, and 2 an outlet for the gases formed in the furnace. These are led through a channel provided with a cooling arrangement 3, with inlet for water at 4, and 90 outlet at 5. The furnace gases are by means of this arrangement rapidly cooled down below 700° C. at which temperature the velocity of the reaction $2\text{CO} = \text{CO}_2 + \text{C}$ is not great. The channel is at 6 divided in 95 two branches one upper and one lower. It may further be provided with obstacles for the gases so as to facilitate the formation of great drops, which when falling through the channel precipitate the finest zinc particles otherwise tending to form a fog. As the channel is divided the velocity of the 100 gases will consequently be reduced and the remaining zinc vapor, which at the prevailing temperature does not follow the gas laws but is a saturated vapor, will separate out from the accompanying "ideal" gas, carbon monoxide, and follow the lower 105

branch of the channel to a closed receptacle 9, while the said "ideal" gas having the greater buoyancy will ascend the upper branch 7 of the channel. The separation 5 is of course not complete and some zinc vapors will follow the upper branch 7, which is provided having a grate 10, with movable bars. On this grate is placed coke or other filtering material, which when the 10 bars are turned gradually falls into the receptacle 9 and is removed therefrom together with the zinc dust which may have been formed.

The chimney above the grate 10 is provided 15 with a cooler 11 and an outlet 8 for carbon monoxide. The outlet may be provided with a water lock in order to keep the system under slight pressure.

The vapor rising through the branch 7, 20 will either become condensed therein or on the filtering material in the form of metallic zinc or zinc dust. The free condensed product will fall back into the lower channel and the receptacle 9, while that retained 25 by the filtering material may be removed therewith, as above set forth. If coke or a similar material is employed it may advantageously be used as the reduction agent in the electric zinc furnace, thus utilizing 30 and recovering the zinc contained in the filtering material.

The lower branch of the channel together with the receptacle 9 serves the purpose of collecting the total amount of zinc condensed 35 and also of condensing the remaining zinc vapor. As the receptacle is a closed vessel, except for the entrance port of the lower branch of the channel, carbon monoxide which may enter the vessel cannot pass 40 through, but will be pressed back into the lower channel.

The zinc dust which is formed during the process may advantageously be subjected to a mechanical action to break up 45 the oxide-film, formed on each particle, so that the particles when free therefrom will melt together. In order to obtain this effect the receptacle may be constructed as a movable or rotating cylinder and may by means 50 of a heating or a cooling arrangement (not shown in the drawing) be kept at a temperature suitable for this mechanical treatment of the zinc dust.

Figures 2 and 3 represent slightly modified 55 examples of my invention, the same reference numerals as in Fig. 1 being employed on similar parts, with primes affixed where the parts have been slightly modified. In Figure 2 the arrangement is mainly the 60 same as in Figure 1 excepting that the gas channel throughout its whole length is provided with water cooling means 3, and that the part of the channel between the furnace and the point where the two branches separate 65 rate is given a gradually increasing cross

section in order to reduce the speed of the gases and facilitate the separation of metal vapor and gas. In addition obstacles 19 are provided upon the upper wall of the channel to further condensation and assure 70 the dripping of liquid metal across the current of metal vapor and dust.

In the example illustrated by Figure 3 the furnace is connected with a chamber 13 through the opening 12. The chamber 13 75 has at its upper end an outlet 14 for non-condensable gases and is at its lower end connected with the closed receptacle 15.

Above the outlet 12 there are placed coolers 16, the lower side of which is provided with obstacles 17 on which zinc may be condensed. The drops may then fall through the chamber thus precipitating the fog already formed. A grate 18 with movable bars on which filtering material is 85 placed, is arranged above the coolers.

From the above it will be observed that the channel itself together with its branches serves as a condensation chamber.

The foregoing detailed description has 90 been given for clearness of understanding and no undue limitation should be deduced therefrom, but the apprehended claims should be construed as broadly as permissible in view of the prior art. 95

What I claim as new and desire to secure by Letters Patent of the United States is:

1. The process of recovering metals from 100 hot vapors thereof, which comprises leading the vapors from the furnace in which they are formed directly into a condensation chamber and subjecting the vapors to immediate and intense cooling, liquefying portions of the vapor in the form of drops, 105 and effecting precipitation of metal dust resulting from the condensation by passing the said liquid metal drops therethrough in opposing direction to the flow thereof.

2. The process of recovering metals from 110 hot vapors thereof in an atmosphere of carbon monoxide, which comprises leading the gas and vapors from the furnace in which they are formed directly into a condensation chamber and immediately lowering the 115 temperature of the gas and vapors to a point below that at which carbon dioxide is readily formed, whereby oxidation of the metal is substantially prevented.

3. The process of recovering metals from 120 hot vapors thereof in an atmosphere of carbon monoxide, which comprises leading the gas and vapors from the furnace in which they are formed directly into a condensation chamber and immediately lowering the 125 temperature of the gas and vapors to a point below 700° C., whereby oxidation of the metal is substantially prevented.

4. The process of recovering metals from 130 hot vapors thereof in a gaseous atmosphere,

which comprises leading the gas and vapors from the furnace in which they are formed directly into a condensation chamber and subjecting the gas and vapors to immediate 5 and intense cooling thus effecting a partial condensation of the metal vapor, dividing the gas and remaining vapors into an upper current and a lower current, interposing in the upper current a filtering medium for 10 additional condensation, and collecting the condensed metal in part on the said filtering material and in part in a receptacle into which the said lower current is directed.

5. The process of removing metals from 15 hot vapors thereof, which comprises leading

the vapors from the furnace in which they are formed directly into a condensation chamber and subjecting the vapors to immediate and intense cooling whereby oxidation of the metal is substantially prevented 20 and the vapor is condensed in part in liquid form and in part as film-covered dust particles, and subjecting the film-covered dust particles to mechanical action whereby the film is removed and the dust particles are 25 fused into liquid form.

Signed at Christiania, Norway, this 19th day of December, 1918.

OYSTEIN RAVNER.
